CLAIM

The ornamental design for a child monitoring device with strap, as shown and described.

DESCRIPTION

The nature and intended use of the article being an ornamental design that permits 2 way communication between parent and child.

FIG. 1 is a front elevational view of the child monitoring device with strap of the present invention;

FIG. 2 is a rear elevational view of the child monitoring device with strap of FIG. 1;

FIG. 3 is a left side elevational view of the child monitoring device with strap of FIG. 1;

FIG. 4 is a right side elevational view of the child monitoring device with strap of FIG. 1;

FIG. 5 is a top plan view of the child monitoring device with strap of FIG. 1; and,

FIG. 6 is a bottom plan view of the child monitoring device with strap of FIG. 1.
